UNITED STATES PATENT OFFICE

154,436

DESIGN FOR A CARRYING KIT

Mohe H. Solworth, Louisville, Ky.

Application March 21, 1946, Serial No. 127,758

Term of patent 7 years

(Cl. D58—4)

To all whom it may concern:

Be it known that I, Mohe H. Solworth, a citizen of the United States, residing at Louisville, in the county of Jefferson and State of Kentucky, have invented a new, original, and ornamental Design for a Carrying Kit, of which the following is a specification, reference being had to the accompanying drawing, forming a part thereof.

The figure is a perspective view of a carrying kit, showing my new design. The side and end not illustrated in the drawing are conventionally plain.

I claim:

The ornamental design for a carrying kit, as shown and described.

MOHE H. SOLWORTH.
